UNITED STATES PATENT OFFICE.

LOREN BUTLER, OF PHILADELPHIA, PENNSYLVANIA.

HEATING APPARATUS.

Application filed November 17, 1921. Serial No. 515,760.

To all whom it may concern:

Be it known that I, LOREN BUTLER, a citizen of the United States, residing at Philadelphia, in the county of Philadelphia and State of Pennsylvania, have invented certain new and useful Improvements in Heating Apparatus, of which the following is a specification.

One object of my invention is to provide improved apparatus which is particularly useful for heating water for household or other purposes by gas, the burner being provided with a pilot tube the flame from which can be adjusted so as not to be extinguished from a strong draught or sudden rush of gas from the burner plate with which the burner is associated.

Figure 1 is a front elevation of my improved burner,

Figure 2 is an inverted sectional plan view taken on the line 2—2 of Figure 1,

Figure 3 is a section taken on the line 3—3 of Figure 1,

Figure 4 is a section taken on the line 25 4—4 of Figure 3,

Figure 5 is a section taken on the line 5—5 of Figure 3, and

Figure 6 is a section taken on the line 6—6 of Figure 3 showing the valve in another position.

Referring to the drawing, the burner 26, which is made in accordance with my present invention, includes an upwardly tapering outlet jet portion 27. The valve stem 29 of the burner 26 has a portion 30 which projects out of the case 31 of the burner and to this portion 30 is attached an arm 32 to which operating means (not shown) can be attached for operating the valve stem by means (not shown) located at a position remote from the valve.

The burner 26 has a pilot tube 73 which always supplies a flame for the purpose of igniting the gas which is admitted to a gas plate (not shown) by the burner and in order to prevent the sudden rush of gas from blowing out or extinguishing the flame of the pilot, I provide a construction clearly illustrated in Figures 1 to 6 inclusive and such construction will now be described.

The valve stem 29 projects from a cylindrical valve 74 which rotatably fits within a cylindrical cavity 75 in the burner case 31. The burner case 31 includes a passage 76 which directly communicates with the gas supply pipe and this passage 35 leads up-

ward to the cavity 75. The jet portion of the case includes a passage 77 which leads upward from the cavity 75 and serves as the outlet passage for the main supply of 60 gas which passes through the passage 76. The valve 74 includes a transversely extending passage 78 which can be moved into a position registering with both of the passages 76 and 77 to supply a full flow of gas 65 through the burner. The valve 74 has a recess 79 cut in its outer peripheral surface; said recess forming a conduit communicating with the transverse passage 81 as clearly shown in Figure 4. Thus when the valve 70 74 is turned as shown in Figure 4 to provide the portion 80 serving as a cut-off for the passage 77, the recess 79 will form a communicating conduit with the passages 76 and 81 so as to supply gas to the passage 81. A 75 duct 71 leads from the transverse passage 81 of the valve to a groove 82 which is cut or otherwise formed in the peripheral surface of the valve; said groove varying in depth as clearly shown in Figures 5 and 6, the 80 groove being deeper at 83 than at 84.

The valve case 31 includes a lateral outlet port 85 which communicates with the cavity 75 at a position registering with the groove 82 and when the valve is in its cut-off position, such for example as shown in Figure 4, the port 85 will communicate with the shallow part 84 of the groove 82. The pilot tube 73 is secured to the valve case and communicates with the port 82 so that when the valve 90 is in said latter position with the shallow part 84 of the groove 82 in communication with the port 85, a small portion of gas will pass through the pilot tube sufficient to maintain a flame of the size for example 95 shown at 86 in Figure 5. When the valve 74 is turned in a counterclockwise direction viewed from Figure 5, the deeper part of the groove 82, which communicates with the duct 81, will move into a position in registry with the port 85 and thereby supply a greater amount of gas to the pilot tube 73 and the size of the flame of the pilot will be increased, as shown at 86^a in Figure 6.

During this movement of the valve the 105 transverse passage 78 will be brought into communication with the passages 76 and 77 and when the inrush of gas takes place the flame 86^a will be of sufficient size to withstand any blasting or blowing action caused 110 by said inrush of gas to the burner plate and consequently there is practically no pos-

2
sibility of the pilot flame being blown out before the quantity of gas passing through the burner has become ignited. My invention thus is capable of preventing asphyxiation of persons by gas in the building in which the apparatus is used and it will be noted that when the valve is again turned off, the flame of the pilot will be reduced in size so as not to waste gas when the burner 10 is not in operation.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

20 Having thus described my invention, what I claim as new and desire to secure by Letters Patent is:—

1. An apparatus of the character described including a gas burner having a case including a cavity, and outlet and supply passages communicating with the cavity; a pilot tube communicating with the cavity; and a valve movably fitting within the cavity and having a transverse passage formed therein and a conduit communicating with the passage and the supply passage when the valve is moved to close the passages, and having a groove of varying depth formed in the peripheral surface thereof and in communication with the transverse passage and with the pilot tube.

2. An apparatus of the character described including a gas burner having a case including a cavity and outlet and supply passages communicating with said cavity; a valve

movably fitting within said cavity; and a pilot communicating with said cavity, said valve having a groove of varying depth in communication with said supply passage and pilot; means located at a place remote from the burner and operatively connected to the valve for operating said valve.

3. Apparatus of the character described including a gas burner having a case including a cavity and outlet and supply passages 50 communicating with said cavity; a valve movably fitting within said cavity; and a pilot communicating with said cavity, said valve having a groove of varying depth in communication with said supply passage and pilot; substantially as described.

4. Apparatus of the character described including a gas burner having a case including a cavity and outlet and supply passages 60 communicating with said cavity; a valve movably fitting within said cavity and including a passage movable into communication with said first passages; and a pilot communicating with said cavity, said valve including a conduit communicating with said valve passage and with said supply passage, said valve also including a groove of varying depth and a duct communicating with said groove and latter mentioned conduit, said groove being opposed to said pilot 70 so that said pilot will receive gas passing into said groove through said duct; substantially as described.

In testimony whereof I have signed my name to this specification in the presence of 75 two subscribing witnesses.

LOREN BUTLER.
